UNITED STATES PATENT OFFICE.

JEREMIAH J. RICHARDSON, OF BROOKLYN, NEW YORK.

FIREPLACE-HEATER.

SPECIFICATION forming part of Letters Patent No. 477,155, dated June 14, 1892.

Application filed April 4, 1885. Serial No. 161,204. (No model.)

To all whom it may concern:

Be it known that I, JEREMIAH J. RICHARDSON, a citizen of the United States, residing at Brooklyn, in the county of Kings and State of New York, have invented certain new and useful Improvements in Fireplace-Heaters, of which the following is a specification.

My invention relates, broadly, to that class of heaters which are known in the trade as "Baltimore Fronts" or "Latrobe Heaters," their general object being to furnish an apparatus which can be utilized by placing the heater in one room and conveying the heat generated therein to another floor for heating an additional room or rooms. These heaters are set into the wall and beneath the mantelpiece, and, in fact, they occupy the space usually set apart for fireplaces or grates. As before stated, these heaters are intended for the heating of at least two rooms, generally one above the other; and my invention contemplates an arrangement and construction of parts whereby the whole or nearly the whole heat from the apparatus can be thrown directly into the room in which it is situated or shut off from said room almost altogether and transferred directly to and utilized in the room or rooms above. To these ends I construct the front portion of the crown of the stove with extensions on both sides in front of the stove-frame, and in connection with such extensions I arrange the vertical direct downdraft flues or pipes so as to be wholly in front of the frame of the heater instead of behind the stove-frame, as has always been the custom heretofore, so that a greater amount of the heat generated in the apparatus may be utilized for warming the room in which said heater is situated. I also arrange in connection with these forwardly-situated upright direct downdraft-flues horizontal flues in the bottom of the heater which carry the heated gases and smoke rearward. At the back of the heater they connect with transversely-situated horizontal flues, which unite with a centrally-divided or double upright smoke pipe or flue arranged to convey the products of combustion upward for heating the room or rooms above. At the rear of the heater and on both sides of same are upright direct downdraft flues or pipes corresponding to those heretofore described as be-

ing in front. These flues are provided with suitable dampers for controlling and regulating the direction of the draft. These upright flues connect with the transverse horizontal flues above referred to, and when the dampers are opened the draft will permit the heated gases and smoke to descend the rear vertical flues and so out and up, thereby transferring the heat direct to the rear of the stove. When, on the contrary, it is more particularly desired to heat the room in which the apparatus is situated, the aforesaid dampers are closed and the direction of the draft forced directly through the front extensions into the forwardly-situated vertical downdraft-flues. The result of this action will be to exhaust the greater part of the heat generated before it leaves the room in which the heater is situated.

Referring to the accompanying drawings, which form a part of this specification, Figure 1 represents a front elevation of a fireplace-heater with my improvements embodied. Fig. 2 is a vertical cross-section of the same on the line X X, Fig. 3. Fig. 3 is a horizontal section on the line Y Y, Fig. 1. Fig. 4 is a vertical cross-section on the line Z Z, Figs. 3 and 5. Fig. 5 is a horizontal section on the line Z' Z', Figs. 2 and 4. Figs. 6 and 7 show a modification, Fig. 7 being a side elevation and Fig. 6 a horizontal section on the line Y' Y', Fig. 7.

A is the front surface of the heater, and B the frame.

C is the upper casting or crown of the heater, having lower plate C'', providing chamber C''' and formed with side extensions C' in front of the frame, from which extend in a downwardly direction the vertical direct downdraft flues or pipes C'. It will be noticed that these extensions and direct downdraft-flues are situated in front of the frame B.

D are horizontal rearwardly-extending flues situated in the base of the heater.

E are transverse horizontal flues, also situated in the base of the heater at the rear. They serve to connect the flues D with the centrally-located rear pipe G. This pipe is divided in the middle, as shown in the drawings, for the purpose of furnishing a separate means of exit for the products of combustion on each side of the apparatus. Normally the

heated products of combustion will enter the extensions C' and the upper ends of the pipes C' directly they leave the combustion-chamber and through said pipes into the horizontal flues D and from these into the transverse horizontal flues F. From these latter the products of combustion will pass into the centrally-divided pipe G, which conveys the products of combustion upwardly.

When it is desired to heat the room in which the apparatus is located, the above is the direction the heated products of combustion are made to take, and by virtue of the extensions C' and the vertical flues C' being placed so far forward the temperature of the room can be easily raised. At the rear of the heater I arrange vertical flues or pipes E, similar in construction to the pipes C'.

In connection with the flues E, I arrange dampers H for opening and closing said flues E. These dampers may be constructed and distributed as shown in the drawings or in any other suitable manner.

In Figs. 4, 5, and 6 I show a handle h for operating the dampers. When these dampers are closed, the operation hereinbefore described would take place—that is, the heated products of combustion would be thrown directly into the forward extensions and flues and the room in which the heater is situated warmed. When, however, it is more particularly desired to heat the room or rooms above, the dampers H are opened and the heated products of combustion, following the more direct draft to the smoke-pipe, will descend the rear flues E instead of the front extensions and flues C' and enter the flues F, passing up through pipe G before it has had time to become cooled.

The arrangement I have shown may be modified somewhat, as shown in Figs. 6 and 7, and the products of combustion may be directed into the extensions C' and forward ends of the flues D, passing through the short flues C''. In this case the latter may be greatly modified in construction, the combustion-chamber being increased in depth and

the products of combustion from the fire-box conducted directly or almost so into the front portions of the horizontal flues D. 50

Are grate-bars set into the tops of the short flues C'' to prevent cinders falling through the latter.

Having thus described my invention, what I claim as new therein, and desire to secure by Letters Patent, is—

1. The combination, in a fireplace-heater having a heater-frame, of the fire-box, the combustion-chamber over the same, the vertical descending flues connecting with combustion-chamber at top, as set forth, and situated in front of the frame of the heater, the horizontal rearwardly-extending base-flues connecting with said vertical flues, and the transverse back base-flues connected with the smoke pipe or pipes, for the purpose set forth.

2. The combination, in a fireplace-heater, of a fire-box, the combustion-chamber over same, the front and rear vertically-descending flues on each side of heater, the latter being provided with dampers, as described, the rearwardly-extending bottom side flues and the transverse horizontal base-flues, and the vertical exit-flues or smoke-pipes, whereby an independent draft is obtained on each side of heater, substantially as shown and described. 70

3. In a fireplace-heater, the combination of a frame, a fire-box, a combustion-chamber over the same, the vertically-descending flues connected to the combustion-chamber and arranged wholly or in part in front of the frame, the rear vertically-descending flues, also connected to the combustion-chamber, provided with dampers, as described, the horizontal rearwardly-extending bottom side flues, the independent transverse bottom flues, and the vertical exit-flue or smoke-pipe divided in the middle, whereby independent drafts on each side of the heater are maintained.

JEREMIAH J. RICHARDSON.
